- wardly-tensioned rods provided with abutment members at the bottom, said abutment members being located above the path of the replacing weft unit and the upper terminals of the rods being located in the path of said reciprocating member except when forced down thereby, and means to actuate the reciprocating member into and out of contact with the rods.
- 10 12. The combination, in a replacing machine, with a stationary support for the under side of slat fabric, of movable abutment means above said support for the upper side of such fabric.
- 15 13. The combination, in a replacing ma-

chine, with a support for slat fabric, of means to force a weft unit into the warp of such fabric along a weft unit previously introduced into the fabric.

14. The combination, in a replacing ma- 20
chine, with a stationary support for slat fab-
ric, and means to force a weft unit into the
warp of such fabric along a weft unit already
in position, of means to prevent the new unit
from buckling while being forced into place. 25
